UNITED STATES PATENT OFFICE.

CLARENCE EDWARD LEFFEL AND JOHN DAVID LEFFEL, OF NIAGARA FALLS, NEW YORK, ASSIGNORS TO THE SPIRELLA COMPANY, INCORPORATED, OF NIAGARA FALLS, NEW YORK, A CORPORATION OF NEW YORK.

ELECTROPLATING-RACK.

1,085,744.

Specification of Letters Patent.

Patented Feb. 3, 1914.

Application filed May 7, 1913. Serial No. 766,147.

To all whom it may concern:

Be it known that we, CLARENCE EDWARD LEFFEL and JOHN DAVID LEFFEL, both residents of Niagara Falls, in the county of 5 Niagara and State of New York, have invented a new and useful Improvement in Electroplating-Racks, of which the following is a specification.

This invention relates to racks for electroplating tanks.

The object of the invention is to provide a simple form of plating rack for carrying or supporting in the electrolyte solution the articles to be plated, and wherein a large 15 number of articles can be suspended out of contact with each other from the same rack, thereby securing a good plating action.

A further object of the invention is to provide a plating rack in which the supports for the various articles are formed with a very small surface in contact with the electrolyte, to thereby reduce the amount of metal deposited upon the supporting members, increase the capacity of the plating tank, and decrease the resistance of the tank, which is usually increased by the deposition of large quantities of the metal upon the supports for the various articles.

A further object of the invention is to provide a plating rack embodying adjustable means for supporting the same at any level beneath the conducting bar, so that the articles can always be immersed at the proper depth in the electrolyte solution, irrespective of its level in the tank.

In the drawings, Figure 1 represents a detail side elevation of a plating rack embodying the invention; Fig. 2 is a similar view, showing the rack adjusted to a different position; Fig. 3 is a plan view of the rack; Fig. 4 is a detail section on the line 4—4, Fig. 1; Fig. 5 is a detail cross section on the line 5—5, Fig. 1; and Fig. 6 is a sectional elevation, on a reduced scale, 45 through an electroplating tank, showing a plating rack in position therein.

The electroplating tank or cell is indicated at 1, and may be of any suitable or preferred size, shape or construction. Above 50 the tank is suitably supported a conductor bar or bars 2, from which the anodes 3 are suspended in the usual manner.

4 represents conductor bars, rods or tubes,

of which there may be any suitable number, from which the electroplating rack and the 55 articles to be plated are suspended.

The electroplating rack comprises a body member 5, in the form of a long bar or rod, which may be of any suitable shape in cross section, in the present case rectangular. 60 Said bar or rod at its opposite ends is provided with upstanding lugs or ears 6, to which are pivotally connected, as on the rivets 7, a pair of suspending or supporting arms 8. These arms cross each other above 65 the middle of the bar or rod 5 and are provided at their upper ends with hook members 9, adapted to be hooked over or around the conducting bar or rod 4. The arms 8 are shown as formed of round bars which 70 are flattened where they cross each other, as at 10, the flattened portions being provided with longitudinal slots or openings 11 through which passes a connecting rivet or pivot member 12. Pivot 12 is slidable 75 loosely in the longitudinal slots of both of the arms 8, for a purpose to be hereinafter referred to.

The main body member or bar 5 is provided along its length with a plurality of 0 closely spaced transverse apertures or openings 13, through which are threaded the supports 14 for the articles to be plated. As shown, these supports are formed of wire of small cross section, and which may 85 be made of any kind of metal, such as copper, aluminum, German silver, steel or the like. The individual supporting members are of U-shape, with their opposite arms threaded through a pair of adjacent apertures 13. The free ends of the supports are bent or deflected downwardly at the sides of the main body member 5, as shown in Fig. 5, and their lower ends are bent into any suitable hook form to receive the articles 15 95 to be plated. Preferably, the apertures 13 are made of a size to receive two of the arms of oppositely disposed supporting members 14, as shown in Fig. 4. Obviously, other arrangements for lacing the wires forming 100 the supporting members 14 through the apertures in the bar 5 may be used, although the arrangement shown is preferred. In any event, such a lacing arrangement will be used as will provide downwardly extending hooks or arms at each end of each of

105

the apertures 13, thereby obtaining the maximum number of supports for the articles 15.

The arms 8 which support the plating rack are adjustable with reference to each other so as to enable the rack to be suspended at different distances below the conductor bar 4, thereby enabling the articles 15 to be plated to be fully immersed in the electrolyte, irrespective of its level, without unduly immersing the plating rack. Comparison of Figs. 1 and 2 shows how the arms can be adjusted with reference to each other by merely altering their angular relation, the pivotal rivet 12 sliding lengthwise in the longitudinal slots 11 during adjusting movement of the arms with reference to each other.

16 represents a loop of strong wire or the like which is passed around the two arms 8, and the opposite ends of which are adapted to engage in notches 17 formed in said arms. By placing the loop 16 in the proper pair of notches 17, the arms 8 may be located in any position, with the main body member 5 at the proper distance above the surface of the electrolyte to just immerse the articles 15 therein.

The body member 5 and arms 8 may be formed of any suitable material, and preferably of copper, steel or other metal of good electrical conductivity, although any conducting material may be used.

The articles to be plated are suspended from the several hooks 14 and the arms 8 are then adjusted to the proper position with respect to the level of the electrolyte in the tank. The hooks 9 are then placed over the conductor bar 4 and the articles allowed to remain in the electrolyte until fully plated. The plating rack with the articles thereon is then removed bodily from the plating tank and the articles washed or cleaned in clean water and then removed from the rack, which is used over again.

The rack described is of large capacity, that is, it enables a large number of articles to be plated in the same tank at the same time. The articles may be supported out of contact with each other so that a good plating effect upon all articles is obtained. Moreover, the supports for the various articles are formed of wire of comparatively small cross section, so that the total surface of the supports immersed in the electrolyte is very small. This reduces the amount of metal plated upon the supports and therefore increases the capacity of a given tank.

Moreover, it takes a longer time for the metal to deposit upon the supporting wires to such an extent as to appreciably affect the resistance of the tank, so that the supporting wires only have to be renewed at infrequent intervals. When coated to such an extent as to affect the resistance of the

tank the wires can be readily removed and new wires threaded through the openings in the bar or rod 5.

What we claim is:—

1. A plating rack comprising a bar or rod provided with a pair of horizontally disposed apertures extending therethrough from side to side, means for suspending said bar or rod from a conductor, and means for supporting articles to be plated, comprising a pair of U-shaped wire members, each member having two parallel arms provided with terminal hooks, the arms of said members being threaded through said apertures in opposite directions to provide a pair of depending hooks on each side of said bar. 70

2. A plating rack comprising a bar or rod provided with horizontally disposed apertures extending therethrough from side to side, means for suspending said bar or rod from a conductor, and means for supporting articles to be plated, comprising U-shaped wire members, each having two parallel arms provided with terminal hooks, the arms of one member being threaded through a pair of said apertures in one direction, and the arms of another member being threaded through a pair of said apertures in the opposite direction, to provide a pair of depending hooks on each side of said bar. 85

3. A plating rack comprising a bar or rod provided with a plurality of closely spaced apertures therethrough, means for suspending said bar or rod from a conductor, and means for supporting articles to be plated, comprising U-shaped wire members, each of said members having a pair of arms provided with terminal hooks, the arms of each member being threaded through a pair of 100 apertures in said bar with the hooks of each member depending on the same side of the bar. 105

4. A plating rack comprising a bar or rod provided with a plurality of closely spaced apertures therethrough, means for suspending said bar or rod from a conductor, and means for supporting articles to be plated, comprising a plurality of U-shaped wire members, each member having two parallel 110 arms provided with terminal hooks, the arms of each member being threaded through a pair of adjacent apertures in said bar in the same direction, the hooks on the arms of some members depending on one 115 side, and the hooks on the arms of other members on the other side of said bar or rod. 120

5. A plating rack comprising a body member, means secured thereto for supporting articles to be plated, and a pair of arms secured to said body member and pivotally connected together, said arms being provided with hooks adapted to be placed over a conducting bar. 125

6. A plating rack comprising a body member, means secured thereto for supporting articles to be plated, a pair of arms pivotally connected to said body member and to each other, said arms being arranged for connection to a conductor, and means for locking said arms in various angular relations.
7. A plating rack comprising a body member, means secured thereto for supporting articles to be plated, a pair of arms pivotally connected to said body member, said arms intermediate their ends being provided with longitudinal slots, and a pivot member passing through the slots of said arms, said arms being arranged for connection to a conducting member, and a loop passing around said arms for locking the same in different adjusted positions.
- 10 8. A plating rack comprising a body member, means secured thereto for supporting articles to be plated, a pair of arms pivotally connected to said body member, said arms intermediate their ends being provided with longitudinal slots, and a pivot member passing through the slots of said arms, said arms being arranged for connection to a conducting member.
- 15 9. A plating rack comprising a body member, means secured thereto for supporting articles to be plated, a pair of arms pivotally connected to said body member and to each other, said arms being arranged for connection to a conductor, and means for locking said arms in various angular relations.

ber, means secured thereto for supporting articles to be plated, a pair of arms pivotally connected to said body member, said arms 20 intermediate their ends being provided with longitudinal slots, a pivot member passing through the slots of said arms, said arms being arranged for connection to a conducting member, and a loop passing around said 25 arms for locking the same in different adjusted positions.

In testimony whereof we have hereunto set our hands.

CLARENCE EDWARD LEFFEL.
JOHN DAVID LEFFEL.
